UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING-MACHINE.

1,149,502.

Specification of Letters Patent. Patented Aug. 10, 1915.

Application filed January 13, 1911. Serial No. 602,386.

To all whom it may concern:

Be it known that I, CHARLES E. DAVIS, a citizen of the United States, residing at Chicago, in the county of Cook and State of Illinois, have invented a certain new and useful Improvement in Mining-Machines, of which the following is a specification.

This invention relates to mining machines, and has for its object to provide a new and improved machine of this description.

The invention is illustrated in the accompanying drawings, wherein—

Figure 1 is a plan view of a mining machine embodying the invention; Fig. 2 is a side elevation of the machine shown in Fig. 1; Fig. 3 is a sectional view taken on line 3—3 of Fig. 2.

Like numerals refer to like parts throughout the several figures.

Referring to the drawings, I have illustrated a mining machine consisting of a frame 1, carrying a motor 2 and the controlling and feeding mechanism, and having projecting therefrom a cutter arm 3, about which moves a suitable cutter chain 4 provided with a series of cutters 5 that engage the material to be cut.

In the use of the machine the cutters engage the material to be cut, as shown in Fig. 1 as they pass across the end of the cutter arm and along one side thereof, and the machine is moved laterally to feed the cutters forward. A flexible power transmitting device 6 is wound upon a drum 7 and passes about a pulley 8, and is then fastened to some fixed device 9. The drum 7 is connected with the motor 2 by means of the gear 10 on the shaft 11, which engages teeth 12 on the interior of the drum. It will thus be seen that by rotating the drum 7, so as to wind up the flexible power transmitting device 6, the machine will be moved toward the fixed device 9.

In view of the resistance to the cutters of the material to be cut, it will be seen that the rear end of the machine will be moved forward more rapidly than the forward end. Some suitable means is provided for preventing the too rapid movement of the rear end of the machine. As herein shown, I provide a second drum 13, which has wound upon it a flexible power transmitting device 14, connected to a fixed device 15 on the other side of the machine from the fixed device 9. Some means must be provided for

controlling the drum 13 to control the unwinding of the flexible power transmitting device in such manner as to keep the machine in proper position as it is fed toward the face to be cut. In the present drawing I have shown a preferred construction for this purpose. The drum 13 is fastened to a sleeve 16 mounted on the shaft 17 (see Fig. 3). Fixed to the sleeve 16 is a beveled gear 18. Loosely mounted on the sleeve is another beveled gear 19. Mounted between the beveled gears 18 and 19 is a gear 20. Rotatably mounted in openings in this gear are the beveled pinions 21, 22, said pinions being held in place by the pins 23. The gear 20 engages a pinion 24 on the shaft 25, said pinion being connected with a notched controlling wheel 26 provided with a series of notches 27. Connected with the beveled gear 19 is a gear 28 which engages a gear 29 on the shaft 30 adapted to be connected with the motor. Associated with the wheel 26 is a controlling arm 31 provided with a projection 32 adapted to fit in one of the notches 27. This arm is preferably provided with a handle 33, so that it can be controlled by hand. The arm 31 is pivoted at 34 and the lower end thereof is connected with the rod or connecting piece 35 pivoted to the lever 36. This lever is pivoted to the frame at the point 37. Rigidly connected with the lever 36 and extending at an angle therefrom is an engaging piece 38 which engages the flexible power transmitting device 6, and which has a projecting part 39 which projects below said flexible power transmitting device. Associated with the connecting piece 35 is a spring 40, which engages a stop 41 on the frame of the machine, and a stop 42 on the connecting piece, so that when the pressure of the flexible power transmitting device upon the part 38 is relieved, the parts are returned to their normal position.

I have described in detail one form of apparatus for carrying the invention into practice, but it is of course evident that the form, construction and arrangement of the parts may be varied without departing from the spirit of my invention.

The use and operation of my invention are as follows: When the machine is in operation the flexible power transmitting device 6 is fastened to the fixed device 9, and the flexible power transmitting device 14 is fas-

105

110

tened to the fixed device 15. The drum 7 is rotated so as to feed the machine laterally against the material to be cut. The power transmitting device 14 on the drum 13 retarded the movement of the rear end of the machine so as to keep the machine in proper position. The drum 13 is rotated by its connection with the motor so as to pay out the flexible power transmitting device to permit the proper feeding of the machine. If the flexible power transmitting device 14 holds the machine back to too great an extent, the machine will be moved to an inclined position with the cutter arm ahead. The flexible power transmitting device 6 then moves the lever 36 so as to rock about its pivotal point. This causes the connecting piece 35 to be moved toward the rear so as to disengage the projection 32 from the notch in the wheel 26, as shown in dotted lines in Fig. 2. The wheel 26 is then released and is free to revolve, thus permitting pinion 24 to revolve and gear 20 to revolve. This gear 20 is normally held against rotation when the wheel 26 is stationary. The drum 13 is now released from its connection with the motor, and the further feeding of the machine moves the rear end around to its proper position, whereupon the lever 36 and connecting piece 35 are moved by means of spring 40, so as to move the projection 32 into one of the notches 27 and stop the wheel 26, thus again connecting the drum 13 with the motor. The retarding device is then again put into operation. It will thus be seen that both the feeding mechanism and the retarding mechanism are directly connected with the motor, so as to be operated thereby; that means are provided for rendering the retarding mechanism more or less ineffective or inoperative; that this means may be automatic or not, as desired; and that complete and accurate control of the feeding of the machine is secured.

45 I claim:

1. A mining machine comprising a frame, a cutter projecting therefrom, a motor mounted thereon, a flexible power transmitting device adapted to be connected with a fixed part at a distance from the frame, a rotatable part on the frame with which said flexible power transmitting device is connected, a retarding device comprising a rotatable drum, a flexible power transmitting device thereon, connected with a fixed part at a distance therefrom, both of said drums operatively connected with said motor so as to be operated thereby, and means for automatically rendering the retarding device inoperative under predetermined conditions.

2. A mining machine comprising a frame, a cutter projecting therefrom, a motor mounted on said frame, a feeding mechanism for feeding the cutter toward the material to be acted upon, comprising a flexible

power transmitting device, a retarding device for retarding the action of the feeding device, said retarding device operatively connected with said motor, a pivoted lever adapted to engage said flexible power transmitting device, a connection between said lever and the operating mechanism of the retarding device, whereby the movement of said lever to a predetermined position, renders the retarding device inoperative.

3. A mining machine comprising a frame, a cutter projecting therefrom, a motor mounted on said frame, a feeding device for feeding said cutter toward the material to be acted upon, comprising a flexible power transmitting device, a drum mounted on said frame, a flexible power transmitting device on said drum adapted to be connected with a fixed part at a distance from the frame, so as to retard the movement thereof, a driving mechanism connecting said drum and said motor, a lever adapted to be engaged by the flexible power transmitting device of the feeding mechanism, and a connection between said lever and the driving mechanism of said drum, whereby the driving mechanism is rendered inoperative when the lever is moved to a predetermined position.

4. A mining machine comprising a frame, a cutter projecting therefrom, a motor mounted on said frame, a feeding device for moving the machine laterally to feed it toward the material to be acted upon, a retarding device for modifying the effect of said feeding device, a connection between said retarding device and a portion of said feeding mechanism, by means of which the retarding device is automatically rendered inoperative under predetermined conditions.

5. A mining machine comprising a frame, a cutter projecting therefrom, a motor mounted on said frame, means for moving said frame and cutter laterally to feed the machine, a retarding device for retarding the movement of the rear end of the machine, comprising a drum rotatably mounted on said frame, a flexible power transmitting device thereon, adapted to be connected with a fixed part at a distance from the machine, a beveled gear connected with said drum, a second beveled gear operatively connected with said motor, a beveled pinion between said beveled gears, a rotatable part upon which said pinion is mounted, a holding device for holding said rotatable part against rotation, so that the drum will be rotated by said motor, and means for releasing said holding device so that it is free to rotate.

6. A mining machine comprising a frame, a cutter projecting therefrom, a motor mounted on said frame, means for moving said frame and cutter laterally to feed the machine, a retarding device for retarding the movement of the rear end of the ma-

- chine, comprising a drum rotatably mounted on said frame, a flexible power transmitting device thereon, adapted to be connected with a fixed part at a distance from 5 the machine, a beveled gear connected with said drum, a second beveled gear operatively connected with said motor, a beveled pinion between said beveled gears, a rotatable part upon which said pinion is mounted, a holding device for holding said rotatable part against rotation, so that the drum will be rotated by said motor, a device for automatically releasing said holding device, comprising a lever adapted to engage a portion 10 of the feeding mechanism, and a connection between said lever and said holding device whereby when the lever is moved to a predetermined position the holding device will be released.
- 20 7. A mining machine comprising a frame, a cutter projecting therefrom, a motor mounted thereon, a feeding device operatively connected with said motor for feeding the cutter toward the material to be acted upon, a retarding device for retarding the movement of the rear end of the machine, and means for automatically varying the effectiveness of the retarding device.
- 25 8. A mining machine comprising a frame, a cutter projecting therefrom, a motor mounted thereon, a feeding device operatively connected with said motor for feeding

the cutter toward the material to be acted upon, a retarding device for modifying the effect of the feeding device, and automatic 35 means for rendering said retarding device inoperative.

9. A mining machine comprising a frame, a cutter projecting therefrom, a motor mounted thereon, a feeding device for feeding the cutter toward the material to be acted upon, a retarding device for retarding the movement of the rear end of the machine, and a controlling device responsive to the angle of inclination of said machine with 40 relation to the direction of its travel for automatically modifying the effectiveness of the retarding device.

10. A mining machine comprising a frame, a cutter projecting therefrom and adapted to cut the material to be acted upon, a feeding device for feeding the cutter toward the material to be acted upon, a retarding device for retarding the movement of the rear end of the machine and means for 45 varying the action of said retarding device, said means responsive to variations in the degree of angularity of said frame.

Signed at Chicago, Illinois, this 22d day of December, A. D. 1910.
